UNITED STATES PATENT OFFICE.

JAMES W. ARROWSMITH, OF MORRISTOWN, NEW JERSEY.

INSTEP-SUPPORT.

1,103,463.

Specification of Letters Patent. Patented July 14, 1914.

Continuation of application Serial No. 268,469, filed July 6, 1905. This application filed March 29, 1910.
Serial No. 552,238.

To all whom it may concern:

Be it known that I, JAMES W. ARROWSMITH, a citizen of the United States, and a resident of the city of Morristown, in the county of Morris and State of New Jersey, have invented certain new and useful Improvements in Instep-Supports, of which the following is a specification.

My invention relates to instep arch supports to be worn in the shoe or boot to support the instep of the wearer and thus to relieve or cure weak or broken down insteps.

Instep arch supports of the class to which my present invention belongs, comprise a metal plate arched to firmly support the instep from beneath and having one side bent or curved upward and so constructed as to afford a somewhat yielding support to the inner side of the instep, together with a cover of leather or other flexible material. In order to afford the yielding side support, it is necessary that the sheet metal of which the metal plate is formed be sufficiently thin to permit it to yield to the pressure of the foot while at the same time it must not permit any material yielding of the support given to the instep from beneath. In other words the metal plate must be yielding in one portion and comparatively rigid in another. For the purpose of aiding in securing the yielding quality in the side of the support, the upturned side has been slit to form tongues as described in U. S. Patent issued to me January 6, 1903, No. 717,523, and as shown in that patent the main portion of the metal plate has been strengthened by a separate reinforcing plate secured to it.

The present invention is designed partly to secure necessary rigidity of the main portion of the metal plate without the use of a separate reinforcing plate and without the use of sheet metal of greater thickness than is desirable in view of the yielding character which it is essential should be possessed by the side.

It is also designed to provide means for preventing the formation of and for intercepting lines of crystallization which usually form transversely to the longitudinal axis of the plate, and to prevent the slits in the side portion from causing the formation of such lines at their inner ends, as well as for other purposes.

With these purposes in view, my invention consists in the construction and combination of elements hereinafter described and particularly pointed out in the claims.

Referring to the drawings: Figure 1 is a bottom plan view of the complete arch support; Fig. 2 is a side view of the same; and Fig. 3 is a cross sectional view on the line 3—3 of Fig. 1.

In the drawings 1 is a metal plate having its main portion 2 arched, to support the instep from beneath, and having one side portion 3 curved or bent upward to afford a side support for the inside of the instep. In order to make the side portion 3 more yielding it is divided by slits into resilient tongues 4, 4. Lengthwise of the plate 1, near the line of junction of the main portion 2 and the upwardly curved side 3, is formed a rib or corrugation 5, preferably projecting downward and preferably as shown lying within the arch of the plate for the purpose of stiffening the longitudinal arch of the plate. This rib is curved and follows the curvature of the plate, with which it is integral. It is also bowed or bent laterally to a slight extent. As a further means of stiffening the support the central portion of the edge of the main plate 2 opposite the upwardly curved side 3 is folded over against the under face of the plate as shown at 6, the line of junction between the plate and the turned over part 6 being substantially straight. The turned over part 6 corresponds in length substantially with the arch of the plate 2 and is received in this arch so that the ends of the plate will rest on the inside of the shoe.

On the upper face of the main plate 2 is secured a covering 7 of leather or similar material which extends on all sides beyond the lines of the plate 1, and is secured to the plate preferably by rivets 8 which are on or near the line of junction between the main portion 2 and the upturned side 3.

By the construction thus described an arch support is formed of one piece of sheet metal having the necessary flexibility in its upturned side and at the same time having the necessary rigidity in the portion which supports the arch of the instep from beneath.

The shape and size of the arch support will be varied to suit different sizes and

shapes of feet and the covering 7 will be cut or trimmed to fit the shoe in which the arch prop is to be worn.

What I claim is:—

- 5 1. An instep support comprising in its construction a plate curved and arched to fit the arch of the instep and having one side turned up to fit the side of the instep and provided with a curved outer edge, the construction and arrangement being such that the plate is depressed and the side portion flexed outwardly under the weight of the wearer, and an integral curved 65 strengthening rib located substantially at the line of junction of the said main plate and its side portion and extending along the same on a line parallel with said junction, but terminating within the edges of the support. 75
- 10 2. An instep support comprising in its construction a main plate curved and arched to approximate the human instep and having a side portion turned up and formed to 80 approximate the side of the instep, the construction and arrangement being such that the main plate is depressed and the side portion flexed outwardly simultaneously under the weight of the wearer, and an integral reinforcing rib located substantially at the line of junction of the said main plate and its side portion and extending along the same from a point near one end to a point near the opposite end, following the arch of the plate 85 at this locality and also curved laterally with respect to the longitudinal axis of the main plate. 90
- 15 3. In a device of the character described the combination of a plate arched to fit the arch of the instep and having an upturned side portion to fit the side curve of the instep and also having said upturned side portion having slits running from the line of its junction with the main portion to its outer edge, and said main portion being provided with a curved strengthening rib at its line of junction with said side 95 portion and between the inner ends of said slits and the body of the main portion and a portion of the edge of said main portion opposite said rib being folded over against the said main portion. 100
- 20 4. An instep support comprising in its construction a main plate curved and arched to fit the arch of the human instep and having a side portion turned up to fit the side of the instep provided with a curved outer edge, the construction and arrangement being such that the plate is depressed and the side portion flexed outwardly under the weight of the wearer, and an integral curved 105 strengthening rib located substantially at the line of junction of the upturned side portion and the other portion of the plate and extending approximately along the base of the said upturned side portion. 110
- 25 5. An instep support comprising in its construction a main plate curved and arched to fit the arch of the human instep and having a side portion turned up to fit the side of the instep provided with a curved outer edge, the construction and arrangement being such that the plate is depressed and the side portion flexed outwardly under the weight of the wearer, and an integral curved 115 strengthening rib located substantially at the line of junction of the upturned side portion and the other portion of the plate and extending approximately along the base of the said upturned side portion. 120
- 30 6. An instep support comprising in its construction a main plate curved and arched to fit the arch of the human instep and having a side portion turned up to fit the side of the instep provided with a curved outer edge, the construction and arrangement being such that the plate is depressed and the side portion flexed outwardly under the weight of the wearer, and an integral curved 125 strengthening rib located substantially at the line of junction of the upturned side portion and the other portion of the plate and extending approximately along the base of the said upturned side portion. 130
- 35 7. In combination with an instep support comprising a part curved and arched to fit the arch of the human instep and a part turned up to fit the side of the instep composed of metal provided with cuts for the purpose of giving it increased flexibility, a strengthening rib extending longitudinally of the support, curved upwardly to correspond therewith and integral therewith throughout its length, said rib located substantially at the line of junction of the said two parts comprised in the instep support. 135
- 40 8. The combination of a plate for supporting the human instep arch curved upwardly from end to end and laterally from side to side and having its medial portion at one side turned upwardly to correspond with the curvature of the inside waist of the human instep and a strengthening rib integral with said plate, extending longitudinally thereof and located substantially at the line of junction of the upturned side portion and the other portion of the plate and extending approximately along the base of the said upturned side portion. 140
- 45 9. Witness my hand this 28th day of March, 1910, at the city of New York, in the county of New York.
